UNITED STATES PATENT OFFICE.

JOHN MACADAM AND WILLIAM BERRY, OF WILMINGTON, DELAWARE, ASSIGNEES TO
JOSEPH BANCROFT & SONS CO., OF ROCKFORD, WILMINGTON, DELAWARE, A COR-
PORATION OF DELAWARE.

CLOTH-FINISHING APPARATUS.

Application filed April 1, 1925. Serial No. 19,775.

This invention, while relating generally to finishing web materials, is more particularly concerned with the finishing of textile materials such as knit or woven cloth of 5 silk, wool, linen, cotton, etc.

The main objects of our invention are to improve the finish of textiles both with regard to surface appearance and feel, and to provide a reliable and efficient apparatus by 10 which the aforesaid operation may be accomplished in a rapid continuous manner.

Other objects and attendant advantages will become readily apparent from the detailed description hereinafter of a typical 15 embodiment of our invention shown in the drawings, whereof,—

Fig. I is a perspective view of our improved cloth finishing apparatus.

Fig. II is a sectional view of a portion of 20 the apparatus taken as indicated by the arrows II—II in Fig. I.

Fig. III is a transverse sectional view taken as indicated by the arrows III—III in Fig. I.

Fig. IV is a fragmentary view showing 25 the arrangement of the cloth-engaging instrumentalities; and,—

Fig. V is a cross sectional view taken as indicated by the arrows V—V in Fig. IV.

Referring first to the complete illustration of the apparatus depicted in Fig. I, 30 "B" indicates the bolt of cloth which is to be treated, said bolt being sustained for free rotation in an appropriate mounting 10 comprising a base board 11 with spaced up-standing brackets 12 to take the ends of the beam 13 whereon the cloth C is wound. The cloth C is continuously drawn from the bolt B by a cooperating pair of inter-geared 35 "pinch" or draft rolls 14—15, which, after common practice, are journalled in end standards 16 and adapted to be driven by a power pulley 17.

Stationed in the spacial interval between 40 the mounting 10 for the bolt B and the draft rolls 14—15, is a mechanism 18 through which the cloth C is passed for surface finishing in accordance with our invention. The elongated supporting frame of 45 this mechanism 18 extends transversely of the path of the cloth C, and comprises a comparatively broad channel member 19 that is sustained at a suitable elevation from the floor, by end pedestals 20 conveniently

formed to the configuration shown from flat 55 bar metal. Located somewhat to the front of the channel member 19 and likewise supported by the pedestals 20, is a tracker bar 21, with its top surface rounded to facilitate passage thereover of the cloth C in the 60 manner illustrated in Figs. I and II. In the present instance, the bar 21 is conventionally represented as being constructed of wood and formed with a longitudinally-extending groove for retainment of an inset 65 strip 22 which may be of metal, glass, rubber or other material depending on the nature of the fabric being treated and the finish desired.

With the tracker bar 21 cooperate an 70 aligned row or series of cloth engaging instrumentalities 23, which from their general appearance and mode of operation may be conveniently termed "tappet hammers". These tappet hammers 23 are mounted for 75 free pivotal movement upon a universal axis rod 24 stationarily supported by brackets 25 secured along the forward flange 19^a of the channel 19 of the frame 18 aforesaid. The tails 26 of the hammers are acted upon 80 by individually-associated rotary eccentric cams 27 fixed with capacity for adjustment, on a common actuating shaft 28, a retractile spring 29 being employed in connection with each hammer to oppose its displacement by 85 the corresponding cam. The shaft 28 is journalled in appropriate bearings 30 secured along the rear flange 19^b of the channel 19; and said shaft is driven through a belt connection 31 with the draft rolls 14—15 90 so that the hammers 23 are intermittently vibrated vertically incidentally to the travel of the cloth C, their heads 32 impounding upon the top surface of the cloth as it moves across inset strip 22 of the tracker bar 21. 95 From Figs. I, II and V it will be noted that the cloth engaging faces 32^a of hammer heads 32 are concaved to conform accurately with the crown of the inset strip 22, and from Figs. IV and V, that said heads are 100 stepped at 33 so that provinces of the faces 32^a overlap, thereby avoiding breaks in the aggregate area which they constitute collectively, and insuring contact with the whole width of the passing cloth. It is to be further noted from Fig. IV that the hammer faces 32^a are cross grooved as indicated at 105 34, the longitudinal grooves being aligned as

105

shown for the purpose of continuity. For convenience of interchangeability, the heads 32 are preferably made separate and detachable from the arms of the hammers 23. These heads 32 are, accordingly, provided with ears 35 spaced to take the ends of the hammer arms, and screws 36 are employed as the means to fasten them.

In practice as the cloth C is continuously drawn over the tracker bar 21, it is acted upon by the tappet hammers 23 which are intermittently elevated and depressed by coordinative operation of the associated rotary cams 27 and springs 29. At each such actuation of the hammers, the faces 32^a of the hammer heads 32 are brought into forcible contact with the cloth, and by virtue of the concurrent reaction of the tracker bar 21, both surfaces of the cloth are more or less similarly affected. In the case of cotton and linen goods, the above treatment results in a lustrous finish, a softer and thicker feel, and a generally improved appearance as of being more closely woven. Variations in the treatment may be had by adjusting the rotary cams 27 angularly so that successive intermittent action of the tappet hammers is secured with a wave like movement of the series after the manner shown in Fig. III, or by substitution of hammer heads characterized by obliquely or otherwise disposed face groovings. Also, if a more extensive treatment is desired, several rows of tappet hammers may obviously be employed for successive operation upon the cloth surface without departing from the spirit of the present invention.

By those skilled in the finishing of web materials, it will be readily appreciated from the inherent simplicity of our improved cloth finishing apparatus, that the same may be run at very high speeds without impairing the effectiveness of the treatment.

Having thus described our invention, we claim:

1. A cloth finishing apparatus comprising an aligned series of tappet hammers adapted to operate upon the cloth surface, the engaging faces of said hammers being cross-grooved and overlapping each other's provinces, and means to actuate said hammers.

2. A cloth finishing apparatus comprising a row of tappet hammers disposed transversely over traveling cloth and adapted to operate upon the surface of the latter, the faces of said hammers being cross-grooved

and overlapping each other's provinces, and rotary eccentric means to actuate said hammers.

3. A cloth finishing apparatus comprising an aligned series of tappet hammers adapted to operate upon the cloth surface, the engaging faces of said hammers being cross-grooved and overlapping each other's provinces, and means to actuate said hammers with a wave-like motion of the series.

4. A cloth finishing apparatus comprising spaced pedestals affording common support for a tracker bar and a series of cooperative tappet hammers adapted to operate upon the cloth surface, the engaging faces of the hammers being cross-grooved and their adjacent ends stepped to overlap each other's provinces, and rotary eccentric means for individually actuating said hammers.

5. A cloth finishing apparatus comprising spaced pedestals affording common support for a tracker bar and a series of cooperative tappet hammers pivoted on a universal axis and adapted to operate upon the cloth surface, the engaging faces of said hammers being cross-grooved and their adjacent ends stepped to overlap each other's provinces, and rotary eccentrics secured with capacity for adjustment on a common shaft for individually actuating the hammers aforesaid.

6. A cloth finishing apparatus comprising spaced pedestals affording common support for a tracker bar and a series of cooperative tappet hammers pivoted on a universal axis and adapted to operate upon the cloth surface, the engaging faces of said hammers being cross-grooved and their adjacent ends relatively stepped to overlap each other's provinces, and rotary eccentrics secured on a common shaft with capacity for relative adjustment whereby the hammers may be coordinated for actuation with a wave-like motion for the series.

7. A cloth finishing apparatus comprising spaced pedestals affording common support for a tracker bar and a series of cooperative tappet hammers pivoted on a universal axis, the engaging faces of said hammers being cross-grooved and their ends relatively stepped to overlap each other's provinces, and rotary eccentrics for individually actuating said hammers.

In testimony whereof, we have hereunto signed our names, at Wilmington, Delaware, this 23d day of March, 1925.

JOHN MACADAM
WILLIAM BERRY.
